UNITED STATES PATENT OFFICE.

GARDNER E. WHEELER, OF NEW HAVEN, CONNECTICUT, ASSIGNOR TO THE ENGLISH & MERSICK CO., OF NEW HAVEN, CONNECTICUT, A CORPORATION.

METAL-BENDING MACHINE.

1,237,732.

Specification of Letters Patent. Patented Aug. 21, 1917.

Application filed June 2, 1917. Serial No. 172,398.

To all whom it may concern:

Be it known that I, GARDNER E. WHEELER, a citizen of the United States, residing at New Haven, in the county of New Haven and State of Connecticut, have invented a new and useful Improvement in Metal-Bending Machines; and I do hereby declare the following, when taken in connection with the accompanying drawings and the characters of reference marked thereon, to be a full, clear, and exact description of the same, and which said drawings constitute part of this application, and represent, in—

15 Figure 1 a top or plan view of a metal bending machine constructed in accordance with my invention.

Fig. 2 a sectional view on the line 2—2 of Fig. 1.

20 Fig. 3 a sectional view on the line 3—3 of Fig. 1, enlarged.

Fig. 4 a perspective view of one of the fold-closing bars detached.

Fig. 5 a face view of one of the guide-plates with the guide-ring connected thereto.

25 Fig. 6 a plan view of a section of strip showing the various stages in the operation of closing the ribs therein.

This invention relates to an improvement 30 in metal bending machines, and particularly to machines for folding strips of metal used in the production of automobile radiators, the object of the invention being to provide a simple arrangement of parts 35 whereby a strip will be readily and evenly folded; and the invention consists in the construction hereinafter described and particularly recited in the claims.

In carrying out my invention I employ 40 a frame or base 7 formed with deep notches 8 on opposite sides, in which notches I locate bearing-blocks 9 for a driving shaft 10. Keyed to the shaft 10 is a hub 11 and secured to opposite ends of the hubs are 45 guide-plates 12 and 13 the inner faces of which are each formed with a series of radial grooves 14, the ends of the grooves being closed by rings 15. Between the guide-plates are a series of fold-closing bars 50 16 corresponding in number to the number of grooves and formed at their opposite ends with guide-ribs 17 which ride in the grooves 14. Between the hub and the bars 55 16 are springs 18 the adjacent faces of the

hub and bar being recessed to receive the 55 ends of the springs as clearly shown in Fig. 2 of the drawings. Arranged at each end of the hub and bearing thereon are bar-cams 19 and 20 the under faces of which have the same curvature as the curvature 60 of the edge of the guide-plate, but stands eccentric to the center of the driving shaft so as to form a cam surface against which the fold-closing bars are pressed. The ends of the bar-cams are formed with notches 21 65 and 22 through which pass locking-bars 23 and 24 which are secured by locking screws 25. Across the top of the frame is a top plate 26 through which adjusting screws 27 and 28 extend onto a thrust plate 29 by 70 which the bar-cams are adjusted. Secured to the locking-bar 24 which is provided with a lug 30 for the purpose, is a presser-plate 31, the lower end 32 of which is concentric with the edge of the guide-plate and the 75 upper end eccentric thereto following the curve of the under face of the bar-cams, the plate being held in place by screws 33. A strip of metal 34 is primarily formed with V-shaped bends or ribs 35 in the usual way, 80 and this strip is passed between the lower end of the presser-plate and the fold-closing bars so that one of the bends will extend between two of the said bars. As the 85 hub revolves the guide-plates are turned and the strip is carried upward, the succeeding ribs entering between the successive bars. As the hub continues its movement the fold-closing bars are moved radially inward, 90 gradually contracting the space between them, and gradually closing the folds in the strip until those folds have been closed together so that the sides of the folds stand parallel, or in other words, the ribs are formed at right angles to the plane of the 95 plate. As the hub continues its movement past the uppermost point, the fold-closing bars gradually move outward so as to release the strip which is discharged from the machine. As the fold-closing bars pass the 100 ends of the bar-cams, they are thrown outward to the limit of their movement by the springs 18 ready to again come into operation when they again pass the lower end 32 of the presser-plate. If heavy stock is used 105 for the strip the inward movement of the fold-closing bars will be less, in which case the bar-cams will be slightly raised. Pro-

vision is thus made for folding strips of varying thicknesses of metal. By moving the fold-closing bars radially in radial grooves, the movement is uniform and great pressure is exerted on the strip.

I claim:—

- 5 1. A metal bending machine comprising two guide-plates formed with radially arranged grooves, a series of fold-closing bars radially movable in said guide-plate, bar-cams against which the fold-closing bars are forced by which the said bars are moved radially inward.
- 10 2. A metal bending machine comprising two guide-plates formed with radial ribs, a hub on which said guide-plates are mounted, rings secured to the edges of said guide-plates and closing the outer ends of the grooves therein, a series of fold-closing bars formed at opposite ends with ribs extending into the grooves in the guide-plate, springs arranged between the hub and said fold-closing bars, bar-cams bearing upon the edges of said fold-closing bars, and a presser-plate adapted to hold a strip of metal in engagement with said fold-closing bars.
- 15 3. A metal bending machine comprising a driving shaft, a hub mounted thereon, guide-plates secured to the opposite ends of said hub, said guide-plates formed with radial grooves, fold-closing bars arranged between the said guide-plates and provided with end ribs entering the grooves in the said guide-plate, bar-cams bearing on opposite ends of said fold-closing bars and tending to force said bars inward, locking bars for holding

the bar-cams in position, and means for adjusting the elevation of the said bar-cams.

4. A metal bending machine comprising a frame formed with notches, bearing blocks located in said notches, a driving shaft mounted in said bearing-blocks, a hub connected to said driving shaft, guide-plates secured to opposite ends of the hub, said guide-plates formed with radial grooves, rings secured to said guide-plate and the outer ends of the said grooves, a series of fold-closing bars located between said guide-plates and formed at opposite ends with ribs entering the grooves in the said guide-plate, springs arranged between the hub and the said fold-closing bars, bar-cams in the path of the ends of the said fold-closing bars, a thrust plate bearing on the upper edges of said bar cams, said bar cams formed at opposite ends with notches, locking bars extending through said notches whereby said bar cams are locked in position, adjusting plates resting on the top of said frame, adjusting screws extending through said adjusting plate and bearing on said thrust plate, and a presser plate extending over the fold-closing bars and tending to hold the strip to be in folded engagement therewith.

In testimony whereof, I have signed this specification in the presence of two subscribing witnesses.

GARDNER E. WHEELER.
